ACTUATING MECHANISM FOR PRESSING MACHINES

Ernest Davis, Syracuse, N. Y., assignor to The Prosperity Company, Inc., Syracuse, N. Y., a corporation of New York

Application July 30, 1941, Serial No. 404,693

10 Claims. (Cl. 38—41)

This invention relates to machines having an opening and closing movement, as garment and laundry presses, and machines having a similar operation, and has for its object actuating mechanism for closing the press from wide open to nearly closed position with a quick movement, and minimum expenditure of power, and a short powerful final closing or heavy pressing movement with a minimum expenditure of power.

The invention further has for its object actuating mechanism in which the source of power is successively operated motors and a coupling which couples the actuating mechanism to the movable element of the press at the end of the preliminary closing movement, this coupling being operated before the motor effecting the final closing movement is energized.

It further has for its object motion transmitting means operated by the final pressure motor of the actuating mechanism successively to the operation of the preliminary closing motor.

The invention consists in the novel features and in the combinations and constructions hereinafter set forth and claimed.

In describing this invention, reference is had to the accompanying drawings in which like characters designate corresponding parts in all the views.

Figures 1 and 2 are side elevations, partly in section, of a pressing machine embodying this actuating mechanism, the parts being shown in their position assumed when the press is open in Figure 1 and closed in Figure 2.

Figure 3 is a fragmentary detail view of the coupling through which the final or heavy pressure closing movement is effected.

Figure 4 is a fragmentary detail view of a modified form in which one motor effects both the preliminary closing and the coupling of the thrust bar to the head-carrying lever.

Figure 5 is a diagrammatic view of the two hand control mechanism for controlling the operation of the press.

Figures 6, 7 and 8 are views similar to Figures 1, 2 and 5 of a slightly different embodiment of the invention.

The pressing machine may be of any suitable form, size and construction, that here shown being of the type in which the relatively movable pressing elements are a stationary buck 1 and a head 2 movable toward and from the buck. The buck is mounted through a suitable bracket 3 on a frame 4. The buck is located above the top or table 5 of the frame. The frame 4 may be of any suitable construction.

6 is a lever pivoted at 7 between its ends to an upright 8 in the rear of the frame, the head 2 being carried on one arm of the lever. The lever 6 is here shown as curved or arcuate, and the other arm 9 thereof extends downwardly into the frame

through the upright 8 which is channel-shaped in cross-section. The actuating means is connected to or coacts with the arm 9 of the lever. The press here shown is power actuated and the actuating mechanism includes successively operated motors for effecting the preliminary closing and the final heavy pressure closing, respectively, and also in one embodiment of the invention, a third motor which shifts motion transmitting parts in motion to transmitting relation at the end of the preliminary closing movement to couple the head-carrying lever in heavy pressure motion transmitting relation to the second motor which effects final heavy pressure. The power used, in the illustrated embodiment of the invention, is compressed air and hence the motors are pressure-operated motors, as cylinders and pistons.

11 designates the cylinder, and 12 the piston therein for effecting the preliminary closing, the cylinder being here shown as mounted to oscillate during the movement of the piston, it being here shown as pivoted at 13 to the frame 4 beneath the table 5 and as extending rearwardly from its pivotal point. The rod 14 of the piston is pivoted at 15 to the rear arm 9 of the head-carrying lever 6. The second motor for effecting the final heavy pressure includes a cylinder 16 having a piston 17 therein, the cylinder being located in the lower part or base of the frame and pivoted at 18 to the frame to have an oscillating movement. The rod 19 of the piston is operatively connected to a thrust bar 20, it being here shown as connected thereto, as by a lever 21 having a long and short arm, the lever being pivoted at 22 to the frame toward the front thereof and the long arm extending downwardly from the pivot and pivoted at 23 to the piston rod 19. The short arm of the lever extends upwardly above the pivot and is pivoted at 24 to the front end of the thrust bar 20 which extends rearwardly in the frame from its pivot 24, it extending in a general tangential direction to the arcuate path of movement of a shoulder 25 on the lever 9, here shown as at the extreme lower end of the lever. The shoulder 25 slidably engages the bar 20 during the preliminary closing of the press, and as here shown, moves along arcuate track 26 on the upper side of the bar 20, the arc of the track 26 being struck from the axis of the pivot 7 of the head-carrying lever 6. The thrust bar 20 is provided at its rear end with a seat or buffer 27 for receiving the shoulder 25 and also with a thrust shoulder 28 adjacent the seat for thrusting against the shoulder 25 at the end of the preliminary closing movement. The shoulders 25 and 28 have a ratcheting action into engagement with each other, and as here shown the bar 20 is mounted to shift about its pivot 24 to provide the ratcheting action to move the shoulder 28 in front of the shoulder 25 at the end of the preliminary closing of the press head 2.

This shifting movement of the bar 20 is here shown in Figures 1, 2 and 3 as effected by a third cylinder and piston motor. 29 designates the cylinder; 30 the piston therein, the cylinder being mounted at 31 to the frame to have an oscillating movement and the rod 32 of the piston being pivoted to a rocking or crank member 33 which is pivoted between its ends at 34 to the frame, this rocking member being connected to the bar 20 by a link 35 pivoted at its upper end at 36 to the bar 20 and at its lower end to the rocking member 33. The rocking member or lever 33 has a crank motion which it transmits through the rod 35 to the thrust bar 20, and owing to this crank motion, the movement of the thrust bar 20 about the pivot 24 to carry the shoulder 28 in front of the shoulder 25 on the head-carrying lever 6 is smooth and without appreciable shock or jar, when the shoulder 25 clears the shoulder 28.

The press is closed against the action of a suitable means, as a spring or springs S tending to open it. The operation, as thus far described to close the press is as follows:

Air is first admitted to actuate the piston 12 and thus preliminarily close the press head 2 down on the work on the buck 1. During this movement, the shoulder 25 slides along the track 26 and at the end of the closing movement, clears the shoulder 28 and seats on the buffer 21. At the same time or immediately after the admission of air to the cylinder 11, air enters the cylinder 29 and tends to actuate the piston 30, but the actuation is blocked until the shoulder 25 clears the shoulder 28 when the piston immediately acts to move the rear end of the bar 20 upwardly about the pivot 24 carrying the shoulder 28 in thrusting relation to the shoulder 25. Air is then admitted to the cylinder 16 to actuate the piston 17 therein and rock the lever to cause the short arm thereof to thrust the bar 20 rearwardly and thus close the press under final pressure upon a short movement of the piston 17. The flow of air is controlled through the cylinders successively by a two-hand control, as will be presently described.

The control here shown for effecting the operation of the cylinder and piston motor 16, 17 successive to the operation of the cylinder and piston motor 11, 12 and 29, 30 comprises a pair of manuals, means operated by the simultaneous operation thereof for opening a master valve which controls the flow of air to the cylinders 11, 29 substantially simultaneously, and a relay valve controlled by the operation of the motor 29 or the piston therein, when it has traveled a predetermined distance on its power stroke and operable to permit the passage of air from the main air line to the power cylinder 16 which actuates the thrust bar to close the press under final heavy pressure, after being preliminarily closed by the cylinder and piston 11, 12.

37 and 38 designate the manuals, these being shown as levers located beneath the front portion of the table 5 and having their handles 39, 40 extending through openings above the table, where they are easily accessible. Each manual operates the movable member or piston 41 or 42 of a pressure-operated motor including a cylinder 43 or 44 in which the piston 41 or 42 works. The cylinder is connected by a pipe 45 or 46 to the pressure side of a diaphragm chamber 47, 48, each having a diaphragm, as 49, therein and having a stem as 50 provided with a valve seat 51 or 52 at its outer end coacting with a

valve head 53 or 54 carried by an arm or lever 55 pivoted between its ends at 56 to an axially movable rod 57 thrusting against the stem of a valve member 58 located in a valve casing 59. The valve member 58 is a combined intake and exhaust valve, and as here shown includes a normally open exhaust valve head 60 and a normally closed intake valve head 61 connected together, so that they act as a unit, the valve being held in its normal position by a spring 62 acting against the intake valve head 61. When the rod 57 is actuated, it closes exhaust valve head 60 and opens intake valve head 61, permitting air to enter from a main air line 63 into the valve casing 59 past the open exhaust valve head 61 through pipe 64 and branch 65 thereof to the intake port 66 in the head of the cylinder 11 to actuate the piston 12 therein on its power stroke, and at the same time air passes from the pipe 64 through pipe 67, the port 68 of the cylinder 29 to actuate the piston 30 therein on its power stroke against the action of return spring 69. When the piston 30 has traveled a predetermined distance, sufficient to move the rear end of the thrust bar upwardly, so that the shoulder 28 of the thrust bar thrusts against the shoulder 25 of the lever 6, the piston passes a port 70 in the side of the cylinder 29, so that air passes through pipe 71 past the check valve 12 to the pressure side of the diaphragm chamber 73 having a diaphragm 74 therein acting on a slide or stem 75, which in turn acts upon one arm of the lever 76 pivoted at 77 between its ends, the other arm of which acts against the stem or push pin 78 slidable in the relay casing 79 against the exhaust valve head 80 of a combined intake and exhaust valve member having a normally closed intake valve head 81 held closed by a spring 82. The two valve heads are connected together to act as a unit and the valve casing at the intake end thereof is connected to a main air line 83.

When air enters the diaphragm chamber 73 and deflects the diaphragm 74 therein, the intake valve head 81 of the relay valve is opened and the exhaust valve head 80 closed, so that air enters the relay valve casing from the main line 83 and passes through pipe 95 to the cylinder 16 to actuate the piston 17, and hence the thrust bar 20.

The stems 50 of the diaphragms 49 are formed with axial passages 84 leading through the valve seats 51, 52 and also opening into the pressure sides of the diaphragm chambers 47, 48. The axial movement of the rod 57 is against the action of a returning spring 85. When both manuals 39, 40 are operated simultaneously, the lever 55 is pushed rectilinearly outward and the rod 57 moved therewith against the action of the spring 85, thus closing the exhaust valve 60 and opening the intake valve head 61. If, however, one manual 39 or 40 only is operated, the corresponding diaphragm in the chamber 47 or 48 only is operated, thus causing the lever 55 to tilt about its pivot 56 and this tilting unseats the corresponding valve head 54 from the valve seat 52 permitting the air to exhaust from the pressure side of the diaphragm through the passage 84, and without moving the rod 57 axially, thus both manuals must be operated substantially simultaneously. The pressure side of each diaphragm chamber 47 or 48 is provided with a check valve controlled inlet 86 to permit the inlet of outside air into the diaphragm chamber.

Release means for opening the press comprises

a release valve for exhausting the air from the pressure side of the diaphragm chamber 73, thus permitting the combined intake and exhaust valve 81, 80 in the relay valve casing 79, which controls the supply of air to the power cylinder 16, to close and the exhaust valve head 80 to open and let air exhaust from the power cylinder 16, and thereby permitting the thrust bar 20 to return to the right (Figure 1) to its normal position. The air in the cylinder 11 releases when the operator lets go of the two hand controls, which he does when the press closes and locks, thus permitting the air to exhaust back through the pipe 64 and out through the valve casing 59. At the same time, air also exhausts from the cylinder 29 through the pipes 67, 64 and valve casing 59. However, the piston 30 in the cylinder 29 is not then retracted by its spring 69 because the thrust bar is held in the position shown in Figure 2 by the friction between the shoulders 25, 28, due to the thrusting of the bar 20 under the action of the piston 17 in the cylinder 16. The air is exhausted from the cylinder 16 to permit the press to open under the influence of the counter spring or springs S by exhausting the air from the cylinder 16 through the valve casing 79 by closing the intake valve head 81 and opening the exhaust valve head 80. This is effected by the release mechanism for releasing the air from the diaphragm chamber 73 while operating the release valve lever 92.

The release valve comprises a casing 90 having a normally-closed, spring-pressed exhaust valve 91 therein, which is opened by a suitable operating lever 92 thrusting against the stem 93 of the exhaust valve to open it. The release lever 92 is shown as located on the front edge of the table 5. The exhaust valve casing has a port therein connected by a pipe 94 to the pressure side of the diaphragm chamber 73. Thus, upon opening of the release valve 90, the air exhausts from the diaphragm chamber 73 permitting the spring 82 to close the intake and exhaust valve head 81 and open the exhaust valve head 80 of the relay valve 79, so that air can exhaust from the cylinder 16 through the pipe 95 out through the valve casing 79, permitting the press to open.

The opening and closing movements of the head 2 are controlled by suitable means to prevent violent action and reaction of the head, or to prevent slamming of the press into finally closed position, but at the same time permit quick preliminary closing, and also prevent violent reaction when the power is released to open the press, but permitting a quick smooth opening of the press head 2 without coming to a violent stop when it approaches wide open position. This means may be a suitable governor or shock absorber 96 having a movable member provided with a crank arm 97 which is connected to the head-carrying lever by a rod 98.

In Figure 4, the function of the cylinder and piston 29, 30 is effected by the cylinder 11 which is the motor means for preliminarily closing the press and also moving the thrust bar 20 into thrusting engagement with the head-carrying lever 6. In Figure 4, the crank member 330 operates correspondingly to the lever 33 (Figures 1 and 2), and is actuated by the re-action on pivot 13 of the cylinder 11 during the movement of the piston therein, and upon operation of the cylinder 11, the thrust bar 20 is operated to the position shown in Figure 2, wherein the shoulder 25 of the lever 6 contacts the shoulder 28 of the thrust bar 20.

In Figures 6, 7 and 8, another embodiment of the invention is shown in which the thrust bar is normally urged as by a spring, into position to engage the shoulder 25 with the shoulder 28, but the spring is not free to act until the press closes through its first or preliminary closing step, and the press is opened by unlatching the thrust bar from the shoulder 25 by power or air pressure. In Figures 6 and 7, the thrust bar 20 is normally under an upward pressure tending to latch the shoulder 28 with the shoulder 25 but upward movement of the thrust bar is prevented when the press is open, by the fact that the shoulder 25 is engaged with the arcuate track 26. When the press closes in the position shown in Figure 7 and the shoulder 25 clears the shoulder 28, the thrust bar is thrust upwardly by a spring 101 thrusting upwardly on a piston 102 in a cylinder 103. The rod of the piston is pivoted to the rear end of the thrust bar at 105. To open the press air is admitted to the upper end of the cylinder 103 through a port 106 which moves the piston downwardly against the action of the spring 101, moving the shoulder 28 downwardly out of engagement with the shoulder 25. When the shoulder 25 is released, the counter-acting springs of the press re-act to open the press. The flow of air to the port 106 through a pipe 107 is controlled by the release lever. The cylinder 103 is provided with a suitable bleeder valve 108 for permitting the air to escape when the piston 102 is being moved upwardly by the spring 101. The bleeder valve, however, is of not sufficient capacity to pass enough air to prevent the piston 102 from being actuated by the air pressure through the pipe 107.

The two hand control for the form shown in Figures 6 and 7 is substantially the same as that shown in Figure 5, with the exception that the release valve permits air to flow through the pipe 107 to the cylinder 103 and also with the exception that the operation of the valve for controlling the flow of fluid to the high pressure cylinder 16 is operated by pressure taken from the low pressure cylinder 11 when the piston 12 has traveled a predetermined distance, on its power stroke, all as will appear in the following description of the operation of the two hand control shown in Figure 8.

Upon the operation of the manuals 39, 40, the valve mechanism in the casing 59 is operated, as in Figure 5, and the air passes from the main line 63 through the valve casing 59, pipe 64 to the cylinder 11 to actuate the piston 12 therein. When the piston has traveled a predetermined distance on its power stroke, this being when the head 2 is preliminarily closed in contact with the work on the buck 1, it uncovers a port 109 in the side of the cylinder 11, permitting air to pass through a pipe 110 past the check valve 72 to the diaphragm chamber 73 to cause the diaphragm 74 thereof to operate the valve mechanism in the valve casing 79 through the lever 76, all as in Figure 5. The air then passes in from the main line 63 through the valve 79 to the final pressure cylinder 16, as in Figure 5. When the mechanism within the valve casing 79 is operated to open the intake valve head 61 and close the exhaust valve head 60, the air passes through a passage 111 into the diaphragm chamber 73 and holds the diaphragm 74 in its operated position, thus locking the press closed. To open the press, the release lever 92 is operated to operate the valve member in a release valve casing 112, this valve member consisting of a

normally open exhaust valve head 113 and a normally-closed, spring-pressed intake valve head 114, these two valve heads being connected together so that they act as a unit. Upon operation of the release lever 92, the exhaust valve head 113 is closed and the intake valve head 114 open, thus permitting air to pass from the feed line 63 through pipe 115 through the valve casing 112 through outlet pipe 116 to the pressure side of a diaphragm chamber 117 to actuate the diaphragm 118 therein, this thrusting through a stem 119 against the lever 76. This operation of the lever 76 releases the valve mechanism 61 within the casing 79, so that the intake head 61 closes and the exhaust valve head 60 opens, permitting air to exhaust from the high pressure cylinder 16. The air exhausts from the cylinder 11 back through the valve mechanism in the casing 59, when the manuals 37, 38 are released. The air also passes from the valve casing 112 through pipe 120 and a check valve 121 therein to the intake port of the cylinder 103, so that when the release lever 92 is operated, the piston 102 in the cylinder 103 is momentarily depressed against the spring 101, thus releasing the shoulder 28 from the shoulder 25 and permitting the press to open.

What I claim is:

1. In a pressing machine including a frame, coacting pressing elements, one of which is movable toward and from the other, and has a two step movement, one a preliminary closing and the other a final pressure movement, and a lever pivoted to the frame and carrying the movable element; the combination of a thrust bar coacting with the lever, the lever being normally disconnected from the thrust bar, and operator controlled power actuating means upon one operation to automatically and successively actuate the lever to effect the first step, and to shift the thrust bar into thrusting relation to the lever at the end of the first step, and actuate the thrust bar to apply the thrust of the same to the lever to effect the second step.
2. In a pressing machine including a frame, coacting pressing elements, one of which is movable toward and from the other, and has a two step movement, one a preliminary closing and the other a final pressure movement, and a lever pivoted to the frame and carrying the movable element; the combination of a thrust bar coacting with the lever, the lever having a shoulder, the thrust bar extending substantially tangent to the arcuate path of movement of the shoulder, the bar also having a surface extending lengthwise thereof with which the shoulder slidably engages during the first step, the bar also having a shoulder located at the end of said surface to engage and thrust against the shoulder on the lever at the end of the first step and operator controlled power actuating means to successively actuate the lever to effect the first step, shift the thrust bar to carry its shoulder into thrusting engagement with the shoulder of the lever at the end of the first step and actuate the thrust bar relatively to the lever and the shoulder thereon to apply the thrust of the bar to the lever through said shoulders to effect the second step, the slidable engagement of the shoulder of the lever with said surface of the thrust bar operating to block movement of the thrust bar by said power actuating means during the first step.
3. In a pressing machine including a frame, coacting pressing elements, one of which is mov-

able toward and from the other, and has a two step movement, one a preliminary closing and the other a final pressure movement, and a lever pivoted to the frame and carrying the movable element; the combination of a thrust bar coacting with the lever, the lever having a shoulder, and the bar extending substantially tangent to the arcuate path of movement of the shoulder, the bar having a surface extending lengthwise thereof with which the shoulder on the lever slidably engages during the first step, the thrust bar having a shoulder at the end of said surface and located to coact with the shoulder on the lever at the end of the first step, the thrust bar having a shifting movement transversely of its thrusting movement to bring its shoulder into coaction with the shoulder on the lever, and operator controlled power actuating means to successively actuate the lever to effect the first step, shift the thrust bar to carry its shoulder into thrusting engagement with the shoulder on the lever and to actuate the thrust bar to apply the thrust of the same through said shoulders to effect the second step, the portion of the actuating means for effecting the shifting of the thrust bar into thrusting relation to the lever including motion transmitting mechanism embodying a rocking member having a crank action, the slideable engagement of the shoulder of the lever with said surface of the thrust bar operating to block the shifting of the thrust bar by said power actuating means during the first step.

4. In a pressing machine including a frame, coacting pressing elements, one of which is movable toward and from the other, and has a two step movement, one a preliminary closing and the other a final pressure movement, and a lever pivoted to the frame and carrying the movable element; the combination of a thrust bar coacting with the lever at the end of the first step, the lever being normally disconnected from the thrust bar and connected thereto in thrusting relation at the end of the first step, motor means connected to said lever and to the bar to successively effect the first step and to move the bar into thrusting relation to the lever, the lever and the bar coacting to block movement of the bar by the motor means during the first step, a final pressure motor and connections between the same and the thrust bar to effect the thrusting movement of said bar, operator-operated control means operable upon single operation to control the successive operations of the motor means and the final pressure motor, and release means for effecting the opening of the press.

5. In a pressing machine including a frame, coacting pressing elements, one of which is movable toward and from the other, and has a two step movement, one a preliminary closing, and the other a final pressure movement, and a lever pivoted to the frame and carrying the movable element; the combination of a thrust bar coacting with the lever at the end of the first step, the lever being normally disconnected from the thrust bar, and connected thereto in thrusting relation at the end of the first step, motor means connected to said lever and to the bar to effect the first step and to move the bar into thrusting relation to the lever, the lever and the bar coacting to block movement of the bar by the motor means during the first step, said motor means including two motors, one connected to the lever and the other to the bar, a final pressure motor, and connections between the same and the thrust bar to effect the thrusting movement of

said bar, operator-operated control means operable upon a single operation for effecting the operation of the final pressure motor successively to the operation of the two former motors, and release means for effecting the opening of the press.

6. In a pressing machine including a frame, coacting pressing elements, one of which is movable toward and from the other, and has a two step movement, one a preliminary closing and the other a final pressure movement, and a lever pivoted to the frame and carrying the movable element; the combination of a thrust bar coacting with the lever at the end of the first step, the lever being normally disconnected from the thrust bar, and connected thereto in thrusting relation at the end of the first step, motor means connected to said lever and to the bar to effect the first step and tend to move the bar into thrusting relation to the lever, the lever and the bar coacting to block movement of the bar by the motor means during the first step, said motor means including a motor connected to the lever to shift the latter, a final pressure motor, connections between the same and the thrust bar to effect the thrusting movement of said bar, operator controlled means operable upon a single operation for effecting the operation of the final pressure motor successively to the first motor, and release means for effecting the opening of the press.

7. In a pressing machine including a frame, coacting pressing elements, one of which is movable toward and from the other, and has a two step movement, one a preliminary closing and the other a final pressure movement, and a lever pivoted to the frame and carrying the movable element; the combination of actuating means including a motor connected to the lever to actuate the same to effect the first step, a second motor and a thrust bar operatively connected thereto and coacting with the lever at the end of the first step, the lever having a shoulder and the bar extending substantially tangent to the path of movement of the shoulder, the shoulder slidably engaging the bar during the first step and the bar having a shoulder for coacting with the former shoulder, the first shoulder being movable into position to be engaged by the last shoulder during the first step, means for shifting the bar to engage said shoulders in thrusting relation, a third motor operable to shift the thrust bar into thrusting relation to the lever, operator-operated control means operable upon a single operation for controlling the operation of the second motor successively to the operation of the first and third motors, and means for releasing the motors to open the press.

8. In a pressing machine including a frame, coacting pressing elements, one of which is movable toward and from the other, and has a two step movement, one a preliminary closing and the other a final pressure movement, and a lever pivoted to the frame and carrying the movable element; the combination of actuating means including a motor connected to the lever to actuate the same to effect the first step, a second motor, a thrust bar operatively connected thereto and coacting with the lever at the end of the first step, the bar extending in a direction tangential to an arc struck from the axis of the lever and having a surface extending lengthwise thereof, the lever slidably engaging said surface during

the first step and having a shoulder arranged to pass off said surface at the end of the first step, the thrust bar being also shiftable radially relatively to the axis of the lever and having a shoulder shiftable during the radial movement into engagement with the shoulder on the lever, when the latter clears said surface at the end of the first step, means for effecting said radial movement of the thrust bar, means for effecting the successive operation of the motors, and release means for effecting the opening of the press, the slidable engagement of the shoulder of the lever with said surface of the thrust bar operating to block radial movement of the thrust bar during the first step.

9. In a pressing machine including a frame, coacting pressing elements, one of which is movable toward and from the other, and has a two step movement, one a preliminary closing and the other a final pressure movement, and a lever pivoted to the frame and carrying the movable element; the combination of actuating means including a motor connected to the lever to actuate the same to effect the first step, a second motor and a thrust bar operatively connected thereto and coacting with the lever at the end of the first step, the lever being normally disconnected from the thrust bar, means for connecting the lever and the thrust bar in thrusting relation at the end of the first step, including a third motor operable to shift the bar into thrusting relation to the lever, the lever and the bar coacting during the first step to block shifting of the bar, motion transmitting means between the third motor and the bar including a member having a crank action, operator controlled means for controlling the operation of the second motor successive to the operation of the first and third motors, and means for releasing the motors to permit the press to open.

10. In a pressing machine including a frame, coacting pressing elements, one of which is movable toward and from the other, and has a two step movement, one a preliminary closing and the other a final pressure movement, and a lever pivoted to the frame and carrying the movable element; the combination of a thrust bar coacting with the lever at the end of the first step, the lever being normally disconnected from the thrust bar, and connected thereto in thrusting relation at the end of the first step, motor means connected to said lever and to the bar to effect the first step and to move the bar into thrusting relation to the lever, the lever and the bar coacting to block movement of the bar by the motor means during the first step, said motor means including two motors, one having cylinder and piston members, one member being connected to the lever and the other member to the thrust bar, the thrust bar having an angular crank arm to which said other member is pivoted, the other motor being a final pressure motor, connections between the same and the thrust bar including a lever to an arm of which the thrust bar is pivoted at the angle of the thrust bar and its angular crank arm, operator-operated control means for effecting the operation of the final pressure motor successively to the operation of the motor for effecting the first or preliminary closing step, and release means for effecting the opening of the press.

ERNEST DAVIS.
